UNITED STATES PATENT OFFICE.

ETTA MANSFIELD, OF NEW YORK, N. Y.

DESIGN FOR A DOLL.

53,480.

Specification for Design.

Patented July 1, 1919.

Application filed December 8, 1917. Serial No. 206,347. Term of patent 14 years.

To all whom it may concern:

Be it known that I, ETTA MANSFIELD, a citizen of the United States, residing in the city, county, and State of New York, have invented a new, original, and ornamental Design for a Doll, of which the following is a specification, reference being had to the accompanying drawing, forming a part thereof.

Figures 1, 2 and 3 are perspective views of the doll, embodying my design viewed from different positions.

I claim:—

The ornamental design for a doll, as shown.

ETTA MANSFIELD.
